INVENTOR.
William H. Martin,

BY
Walter N. Haskell,
his ATTORNEYS.

UNITED STATES PATENT OFFICE.

WILLIAM H. MARTIN, OF DAVENPORT, IOWA.

BALING MACHINE.

Application filed March 10, 1920. Serial No. 364,744.

To all whom it may concern:

Be it known that I, WILLIAM H. MARTIN, a citizen of the United States, residing at Davenport, in the county of Scott and State of Iowa, have invented certain new and useful Improvements in Baling Machines, of which the following is a specification.

My invention has reference to baling machines, such as are used in baling paper, rags, 10 and similar material, and it is an improvement on a machine of that class for which Letters Patent of the United States No. 1,133,048 were issued to Fred A. Lundahl Mar. 23, 1915. The chief purpose thereof is 15 to improve the general construction of the machine, so as to increase the efficiency and operation thereof.

During the baling operation a considerable amount of force is exerted upwardly, 20 through the compressing devices, so that the superstructure which carries such devices must be specially designed and constructed for the work required of it, and be positively held in place when the contents of the machine are under compression. One of the 25 features of the present invention is a superstructure, or supporting frame for the plunger mechanism, which possesses a combined strength and efficiency exceeding that of other similar machines.

In the drawings:

Fig. 1 shows the invention in front elevation.

Fig. 2 is a vertical section on the broken line 2-2 of Fig. 1.

Fig. 3 is a plan view of the supporting frame for the compressing devices.

Fig. 4 is an end view thereof.

Fig. 5 is a cross-section through the rear 40 wall of the machine.

Fig. 6 is a detail of the upper door locking mechanism.

The device comprises a receptacle, formed of side plates 1, a rear plate 2, and a front door 3, hinged to one of the side plates, and provided with a drop portion 4, hinged to the part 3. The door 3 is held normally in a closed position by means of a catch 5, pivoted to the front of the door and engaging a frame 6, swingingly mounted at one side of the door. The section 4 is held in a closed position by means of a shaft 7, rockingly supported near the upper edge of the door, and provided on its ends with latches 8, adapted to engage catches 9 on the side plates 1. At a central point on the shaft 7 is a han-

dle 10, by means of which the latches 8 can be released, and which also acts as a weight, to hold said latches against accidental release. When the section 4 is opened, the 60 downward movement thereof is limited by means of arms 11, pivoted at their upper ends thereto, and slotted at their lower ends for engagement with pins in the edges of the part 3. When the section 4 is returned to 65 a closed position the latches 8 will automatically engage the catches 9, such latches being held in an engaging position by a projection 12 on the handle 10, bearing against the face of the door. 70

The machine is provided with a supporting frame, or superstructure, consisting of two pairs of parallel cross-plates 14, united at their ends by plates 15, extended in each direction beyond the side-plates. In the end-plates 15 are bearings 16 for a shaft 17, on which is fixed a pinion 18, in engagement with a rack 19, on one end of which is a plunger 20. The rack 19 has a rib 21 which has vertical play in an extension 22 of a 80 frame 23, centrally of the frame 14, and accommodating the pinion 17. Projected rearwardly and downwardly from the rear cross-plate 14 is a pair of wings 24, spaced so as to pass downwardly just within the side 85 plates of the receptacle, to which they are pivotally attached, as at a. By this means the supporting frame is permitted to tip rearwardly, carrying with it the compression devices, as shown in Fig. 2. Extended forwardly in line with the wings 24 are lips 25, which project downwardly just within the side walls of the receptacle when the parts are in an operative position, and assist in holding the superstructure from side play. 90 The extensions 24 and lips 25 also assist in maintaining the walls of the receptacle in proper rectangular position with relation to each other. 95

The forward edge of the superstructure is 100 provided with a pair of openings 26, adapted to receive latches 27, pivoted to the side plates 2 near the upper edges thereof, and holding the superstructure from upward movement when the contents of the machine are under compression. When it is desired to clear the top of the machine, the latches 27 are swung forwardly, as shown in Fig. 2 of the drawings. The latches 27 and latches 8 combine to keep the forward edges of the 110 side walls 2 of the receptacle from spreading when the machine is under pressure.

The rear wall of the receptacle is preferably formed of vertical side-plates 28 having outwardly projected flanges 29 on their inner edges, and central plates 30, having similar flanges 31 on their edges, said flanges being spaced apart to permit the passage of cords or wires, for binding the bale after it is formed. The angle-plate formation also serves to add strength to said rear plate.

10 The shaft 17 is operated by the hand-wheel 32 to raise the plunger 20, while the shaft is rotated in the opposite direction for compression purposes by means of a ratchet-wheel 33 on said shaft, and an operating bar 34, the latter devices being of well-known construction.

15 The parts 14, 15, 22, 23, 24, and 25 are integrally formed, instead of being constructed of a supporting plate and devices mounted thereon for holding the compressing mechanism, as has heretofore been the case. The unitary construction not only enables this part of the machine to be more cheaply produced, as by casting, but it also 20 forms a strong and compact frame, well fitted to resist the strain which is placed thereon during the compression operation.

What I claim, and desire to secure, is:

25 1. In a device of the class described, the combination of a receptacle provided with a hinged closure on one of its sides; a frame formed of two pairs of parallel cross-plates united at their outer ends by plates provided with wings extending rearwardly between

the receptacle walls, and hingedly connect- 35 ed therewith, a rectangular frame at the inner ends of said cross-plates, forming a central vertical guide-way, said end-plates and guide-way being fitted with transverse shaft bearings; lips at the forward edge 40 of said first-named frame projecting between the side-walls of said receptacle; slotted extensions at the forward edge of said first named frame; latches pivoted on said receptacle adapted for engagement with 45 said extensions, to hold said first-named frame in closed position; and compression devices provided with a central controlling member vertically movable in said guide-way.

2. In a device of the class described, a supporting frame comprising two pairs of parallel cross-plates united at their outer ends by plates provided with downwardly and outwardly extending wings adapted for 50 pivotal connection with the receptacle of a baling machine, and at their inner ends by a rectangular frame, a pair of lips projected downwardly from said first-named frame, at the edge thereof opposite to said wings, slotted extensions adjacent to said lips, capable of receiving swinging latches, and a guide-way centrally of said rectangular frame, all of the parts of said frame being integrally formed.

In testimony whereof I affix my signature.

WILLIAM H. MARTIN.
